UNITED STATES PATENT OFFICE.

SAMUEL W. ROHN AND RUFUS N. SHELDON, OF NORWALK, OHIO.

BAG-FASTENER.

No. 889,046.

Specification of Letters Patent.

Patented May 26, 1908.

Application filed August 21, 1907. Serial No. 389,493.

To all whom it may concern:

Be it known that we, SAMUEL W. ROHN and RUFUS N. SHELDON, citizens of the United States, residents of Norwalk, in the county of Huron and State of Ohio, have made a certain new and useful Invention in Bag-Fasteners; and we declare the following to be a full, clear, and exact description of the same, such as will enable others skilled in the art to which it appertains to make and use the invention, reference being had to the accompanying drawings, and to letters or figures of reference marked thereon, which form a part of this specification.

Figure 1 is an end view of the invention as applied. Fig. 2 is a side view of the same. Fig. 3 is a plan view of the invention. Fig. 4 is a side view of the same. Fig. 5 is an end view of the invention bent into form the elastic or spread position of the arms being indicated in dotted lines.

The invention relates to means for fastening the mouths of paper bags or sacks in order that the contents may be kept intact, and it consists in the novel construction and combinations of parts as hereinafter set forth.

In the accompanying drawings, illustrating the invention, the letter *a*, designates the sack, the mouth or open upper end portion of which is first turned or twisted to close such mouth or end and form a contracted approximately cylindrical end. Over this contracted end is slipped or dropped the circular appliance *b*, which is preferably formed of flat or sheet metal of pliable nature, by having the central circular portion struck or stamped from a circular blank leaving a flat

annulus or ring, the opening of which is designed to receive the contracted or twisted end of the sack. This annulus *b*, which is quite thin, may have a central depression therein, shown at *b'*, to serve as a guide in making the central bend therein.

In use, after the device is in place upon the sack it is bent upward in the center with the thumb and finger of one hand into V-form in edge view, when the tendency of the twisted end of the sack to expand will to some extent force the two diverging semi-annular branches *c*, *c*, of the bent annulus apart without, however, forcing apart the bends *d*, connecting such branches, whereby the branches *c*, *c*, of the annulus will clasp such twisted mouth in an elastic manner, the force of such clasping action increasing with the expansion of the sack end and the spread of such halves.

In practice the mouth of the sack will be kept effectually closed and the contents of the sack cannot escape.

Having thus described the invention, what we claim and desire to secure by Letters Patent is:

A bag fastener consisting of a thin pliable metallic clasp having divergent semi-annular branches and V-form bends connecting said branches.

In testimony whereof we affix our signatures, in presence of two witnesses.

SAMUEL W. ROHN.
RUFUS N. SHELDON.
